UNITED STATES PATENT OFFICE

CHARLES EDWARD STEVENS AND ARMAND MAMOR, OF ANTWERP, BELGIUM,
ASSIGNORS TO INTERNATIONAL STANDARD ELECTRIC CORPORATION, OF NEW
YORK, N. Y.

TELEPHONE SYSTEM

Application filed April 24, 1930, Serial No. 446,876, and in Great Britain July 17, 1929.

This invention relates to telephone systems and more particularly to telephone systems of the kind in which connections to the subscribers' lines of an automatic or semi-automatic telephone system are established by means of alternating current impulses.

In such telephone system it is usual to interconnect the exchanges by two-wire trunk lines which at both ends are provided with means for sending and receiving alternating current impulses, which co-operate with the local switching and controlling devices in the establishment of a connection between the subscribers of the exchanges or between an operator and a wanted subscriber. Hitherto it has also been usual to use different trunk lines for connections in opposite directions.

According to a feature of this invention, a trunk line is provided which is adapted to two-way working. This feature is particularly useful in cases where the outgoing traffic of an automatic exchange is too small during certain hours to justify the presence of a toll operator at this exchange, as it may be the case during night hours and with a rural exchange. In such a case it is therefore desired to place the outgoing traffic of this exchange under the exclusive control of an operator located at the desired distant exchange during such hours.

According to a further feature of the invention this is obtained by adapting the said trunk line for use as a dialling trunk for calls from a distant exchange to the automatic exchange and as a recording trunk for calls in the opposite direction.

For this purpose a switching device or key may be associated with the local recording trunk at the automatic exchange whereby it is possible to disconnect this trunk from the local toll position and to prepare the connection of the local recording trunk to the outgoing trunk circuit which is completed upon the call being extended from an automatic subscriber to the said local recording trunk. Means may also be provided which, upon such a call, cause the transmission of an alternating current im-

pulse to the distant toll position to indicate therein the presence of a call, and furthermore means may be associated with the said local recording trunk which upon such a connection become effective to make the local recording trunk busy for other calls and to put it under the exclusive control of the distant toll operator.

According to still another feature of this invention means are provided at the automatic exchange end of the trunk line which upon a call from the distant exchange co-operate with the switching and controlling devices of a connecting circuit attached to the trunk line to transmit alternating current impulses to the distant exchange for the purpose of progress indication and the supervision of the connection. The said means may comprise a group of relays controlled by the connecting circuit at the automatic exchange and at the distant exchange a group of relays which are related to one another in such a manner that different signals are given to the toll operator by subsequent alternating current impulses received from the automatic exchange.

According to another feature the relay device is provided in the said connecting circuit which upon a premature release of a connection takes care of any new call initiated by the said toll operator during the release of the connecting circuit, the said relay device being caused to operate upon such a call and to lock up in order to restore the apparatus of the connecting circuit to normal and to start its operation for the said new call. The said relay device may be also arranged to take care of "faulty" calls, which for instance may be created by discharges on neighboring lines, in which case it causes the connecting circuit to restore to normal.

Further features of this invention will appear from the following detailed description of one particular embodiment of the invention illustrated in the accompanying drawings, in which Fig. 1 shows a toll operator's position at a distant exchange, an incoming trunk circuit at an automatic exchange, a local recording trunk and a local

toll operator's position; whereas Fig. 2 shows a connecting or cord circuit which is adapted for use with the said incoming trunk circuit.

- 5 Referring now to Fig. 1, A is a toll operator's position located at a distant toll exchange from which a trunk line T is leading to an automatic exchange B.

At the toll exchange end of this trunk 10 there are provided a jack LJ and a lamp CL, which serve for both outgoing and incoming calls. Further, an individual dialling key DK and an individual ringing key RK are associated with this trunk line. 15 At the automatic exchange B, this trunk terminates on a toll 1st group selector TIGS (Fig. 2) and by means of a certain number of relays, a call can be originated by the toll operator: It may be seen from the drawings that the toll trunk line T is connected straight to the cord circuit CC, but it will be readily understood that it is also possible to associate the cord circuit with a line finder number of such trunk lines. A call originated by a subscriber of the automatic exchange B is extended by switching means which are not shown in the drawings to the local recording trunk LT. This local recording trunk is thereupon connected to the 20 trunk line T and the call will be received at the distant exchange to position by means of a lamp signal. In the latter case, the trunk line is disconnected from the toll 1st group selector TIGS.

- 25 The circuit operation is as follows:

A. Toll to automatic exchange

When the toll operator plugs into the line jack LJ (Fig. 1) relay Tr operates and on 40 its left change-over combination it switches over the front contact of the incoming impulse repeating relay Dr to the set of relays Jr, Hr and Kr, the functions of which will be given later, and at the right change-over combination of Tr, the circuit for relay Ar is closed. The latter relay operates slowly, having a resistance in series with its winding, and so allows Br to operate via the back contact of Ar to front of Tr, and to be 45 saturated before its circuit at the back of Ar is opened. To the front of Br, relay Er also operates, and at its front contacts a short alternating current impulse is sent out to the toll trunk line. In fact, after relay Ar has 50 operated and the circuit for Br is opened, the latter relay releases slowly, and in turn Er also releases. At the right inner front of Ar, the resistance in series with its winding is short circuited, and at the left outer 55 front of the same relay, a circuit is closed for relay Cr, which remains energized during the time of the connection. At the front of Cr, a circuit is prepared for Br, which circuit will be completed when Tr releases at 60 the end of the connection.

By the alternating current impulse sent out to the toll trunk line, the alternating current impulse relay Rar in the automatic exchange operates, and to its front Rbr also operates. By the front of Rbr and via the back of R_{he} sequence switch R of the toll 70 group selector is moved out of its normal position and runs to position 3, where the toll group selector circuit picks up a free register and then advances to the position in which it awaits the dialling.

When relay Rbr in the incoming trunk circuit operates, relays G_{lr} and B_{r_{rl}} (Fig. 2) operate in parallel, to the front contact of relay Rbr, and by the front of B_{r_{rl}} the sequence switch of the toll group selector is moved out of position 1. Relay B_{r_{rl}} locks until 1½, via its front contact. At the left middle front of B_{r_{rl}}, ground is connected towards relay Rd, in the local recording 80 trunk LT (Fig. 1) which operates and makes the latter circuit busy assuming that the night key NK is thrown. After position 1½ the ground for the mentioned relay is supplied from the right outer contact of cam F. In position 2, relay G_{lr} is still connected towards the front of relay Rbr, and G_{lr} will release only after the impulse is over, and at the back of G_{lr} the sequence 85 switch will be moved out of position 2.

Beginning from position 2, the slow releasing relay P_{rr} is connected via cam K to the back of Rbr, and from this moment on the selector is under control of this relay. In fact, this relay will keep energized 100 during the train of impulses, and will release only in case a release impulse is given, which is long enough to cover the releasing time of P_{rr}. Relay P_{rr} controls, over its back contact the break down relay B_{rl}, 105 which, when once operated, locks between 3/18 to cam F. The functions of this relay will be given in connection with the various cases of premature release.

In position 3, the register chooser RC 110 which is shown at the bottom of Fig. 2 is connected via cam I to the back of G_{tr}, and it will start to hunt for a free register which is not shown in the drawings. When a free register is picked up relay G_{tr} operates via the test brush "g" of the register chooser and cam T, by its high resistance winding, and as soon as it makes its front contact it introduces its secondary winding in series with Sh_r, in parallel to its high resistance winding, making the register busy. Relay Sh_r is slow acting, and is provided to prevent double connections. To the front contact of Sh_r, relay G_{lr} operates, and at its 120 front contact the sequence switch is moved out of position 3. Beginning in position 3, from cam F left inner, via the back contacts of B_{r_{rl}} and P_{gr}, a ground is connected to the armature of B_{fr} (Fig. 1) by which re- 125

lay S_{01r} is energized via back of S_{02r} and back of Bfr .

Beginning in position 4, a ground is given, via cam M, to energize relay Bfr , in the incoming trunk circuit, and by this change in the trunk circuit an impulse is given towards the toll operator, causing the supervisory lamp CL to flash. This is an indication to the toll operator at the distant exchange that she may start dialling.

The combination of relay Bfr and the slow releasing relays S_{01r} and S_{02r} in Fig. 1 serves to give impulses, towards the toll operator, of the progress of the call. This is done in the following way: As soon as relay Bfr operates, it disconnects at its back contact relay S_{01r} , and prepares a circuit for relay S_{02r} . Since relay S_{01r} is slow releasing, relay Rer will get a chance to operate, for a short time, via front of S_{01r} and front of Bfr . By fronts of Rer an impulse of alternating current is sent out to the distant toll office. To this impulse, the alternating impulse relay Rr at the toll position operates and Dr also operates in turn. It may be remarked that the lamp CL associated with the line jack LJ is caused to light, as soon as the operator inserts the plug, via the following circuit: back of Gr , back of Hr to the right inner front of Tr .

By the impulse received, a circuit is closed at the front of Dr for relays Kr and Hr in series. Relay Kr , being a marginal relay, will not operate, but relay Hr will operate and locks via its front contact to the right inner front of Tr . At the right outer front of Hr a circuit is prepared for relay Jr , to the back contact of Dr , and as soon as the impulse is over, relay Jr also operates and locks to its own front contact. At the change-over combination of Hr , the lamp CL is switched over, via back of Kr , to the flashing interrupter FLI . The lamp will start flashing, and this is an indication that a register is picked up and the toll operator may start dialling.

The operator will throw the dialling key DK and will dial the full number wanted. When the dialling key is thrown, relay Sr operates in series with the dial, and when the dial is wound up, relay Er also operates to the off-normal contact of the dial. At every opening of the dial, relay Sr is released, and at its back contacts and via front of Er , the dialling impulses, by means of the alternating current, are sent out to the line.

As mentioned in the foregoing the toll group selector circuit has advanced to the dialling position 4 in which the instepping circuit of the register, via brushes "a" and "b", is closed via back contact of Irr and cam P , in series with a resistance. At the same time, the impulse repeating relay Irr is connected via cam L , back of Pgr towards

the front of Rbr . The impulses sent by the toll operator are received by the alternating current relay Rar and by the impulse repeating relay Rbr , which transmits the impulses to the register.

After all digits have been sent in, the dialling key is restored, and the operator awaits the completion of the connection.

When the register is ready to make the first selection relay Glr operates via cam E and brush "d" to the register, and at the front of Glr the sequence switch is advanced to position 6, where relay Glr remains locked by its left hand front contact, via cam S and brush "d", to the same circuit. In position 6, the trip spindle P_2 of the selector is set, via cams C and I, to the front of Glr , in the known manner, and after the last impulse, when the short circuiting contact on INT.2 is opened, Glr releases, and on its back contact drives the sequence switch out of position 6. In $6\frac{3}{4}$, Glr is connected via cam D, back of $Brrl$ to the back contact of Gtr and to the front of Glr the brush carriage P_1 will start to rotate, via cams C and I. When a free trunk has been picked up, Gtr energizes by its outer and inner windings in series, and by its front contact it introduces its secondary winding, making the trunk busy. At the back of Gtr , the circuit for Glr is opened, and at the back contact of the latter, the sequence switch is driven out of 7, through $8\frac{1}{2}$ and $9\frac{1}{2}$ to the selection beyond position $10\frac{1}{2}$.

If the brush carriage should not succeed in picking up a trunk in position 7, due to double test, repeated hunting in position $8\frac{1}{2}$ will take place, since Glr will again energize in the same circuit to the back of Gtr . If, due to a premature release, the brush carriage is started out of its normal position but does not pick up a free trunk, it will be restored in position $9\frac{1}{2}$, since Glr will find a circuit via cam E to the back of Gtr , and will drive the brush carriage home. When reaching the home position, the contact of $G.INT$ will be closed and Gtr will be caused to energize, disconnecting Glr and on the back of the latter the sequence switch will be moved out of $9\frac{1}{2}$.

In position $10\frac{1}{2}$, the register's fundamental circuit is connected via brushes "c" and "d" and cams R and S towards the next selectors. It will be remarked that relay Csr is connected towards the register via cam O and brush "e", beginning from $8\frac{1}{2}/10\frac{1}{2}$, and thus the cord circuit is under the control of the register. When the register has completed the selection, the ground for Csr is removed in the register, and this relay releases and in turn Gtr operates to the back of Csr , and moves the sequence switch out of position $10\frac{1}{2}$, running to position 12, which is the "ringing or busy" position. In $11\frac{1}{4}$, the ground at cam M is opened, and

this causes the release of relay Bfr , in the trunk circuit.

It will be remembered that at this moment, relays Hr and Jr are energized, and lamp CL is flashing. At the incoming end, relay Bfr is energized, and also So_1r is energized, via back of So_1r and front of Bfr . When the selection is completed and the toll group selector leaves the selection beyond position, the circuit for relay Bfr is opened as already mentioned and this relay releases, and in turn So_1r also releases, but being slow releasing, relay Rer will energize for a short while, via front of So_1r and back of Bfr , thus sending out again a short impulse towards the distant toll office. By this second impulse, received by relays Rr and Dr , relay Hr will be short circuited via the right inner front of Jr , and thus Hr will release, but at the same time, the marginal relay Kr will operate via the right inner front of Jr to front of Dr , and will lock by its outer winding to the front of Tr . Relay Jr will keep energized by its inner winding, via its left hand front to the front of Dr , as long as the impulse lasts, but will release when the impulse is over, since the circuit of its outer winding is opened at the front of Dr and the circuit of its inner winding is opened at the front of Hr . Lamp CL will stop flashing and will light steadily, via back of Hr to front of Tr , as at the beginning.

If the called subscriber's line has been found free, the final selector will run to the ringing position and will send out intermittent ringing in the regular way. As soon as the called subscriber answers, relays Csr and Cs_1r operate in series, via the subscriber loop, and at the front of Csr the sequence switch is moved out of position 12, running to the talking position 13 where relay Bfr is placed under the control of the automatic subscriber. In this position relay Bfr , being connected via cam M to the front of Csr , will again operate and again an impulse is sent out to the line by means of the slow releasing relays So_1r and So_2r , which impulse again causes the energization of relay Hr and in turn also of relay Jr . When Hr operates, the lamp CL extinguishes and thus shows that the called subscriber is on the telephone. Any further change by the automatic subscriber will cause a change in the relay Bfr , which in turn will always send out an impulse towards the toll office, and will cause a corresponding change in the state of the relays Hr and Jr . In this way, the supervision of the automatic subscriber is obtained.

If the called subscriber was found busy, and thus the sequence switch stopped in position 12, relay Cs_1r is caused to energize steadily, from the final selector, and Bcr will release, which relay, as may be seen, was energized beginning from $11\frac{1}{4}$, via

back of Cs_1r to ground on cam Q . At the back of Bcr , in series with the busy flash interrupter, the circuit for relay Bfr is intermittently closed, and thus impulses will be intermittently sent out to the line, and lamp CL will be caused to flash, giving an indication to the toll operator that the wanted subscriber is busy. The speed of the busy flash interrupter in the group selector is different from that of FLI and this fact allows the toll operator to discriminate between the busy flashing and the flashing caused by the interrupter FLI .

It must be remarked that if the line was found free, the battery from the final given to Cs_1r is only temporary, during a passing contact, and is not given long enough to cause the release of the slow releasing relay Bcr . If, in the talking position, the called subscriber leaves the telephone and it is desired to re-ring him, the toll operator throws the ringing key RK , and in this way relay Er is caused to energize to a ground at the ringing key, and relay Sr energizes intermittently, via the interrupter FLI . Thus alternating current is sent out to the line intermittently and to these impulses relays Bcr and Rrr operate in parallel, via cam Q , back of Pgr , to the front of Rbr . Relay Bcr will keep energized during the interval of impulses, whereas Rrr will release and thus the ringing relay Rsr will energize via back of Rrr and front of Bcr , to ground on cam J . Relay Rsr , once energized will lock by its front contact to front contact of Bcr , as long as the ringing impulses last. At the fronts of Rsr , steady ringing current is sent out to the subscriber's line. It will be observed that during talking i. e. when Cs_1r is energized, relay Rrr is also energized to the front of Cs_1r , and thus, if the toll operator sends out ringing by mistake, no ring would be sent to the subscriber's line.

If, when the connection is finished, the called subscriber releases first, lamp GSL will light to the back of Csr . Due to the fact that this cord circuit is used for toll connections, it is not desirable to have lamp GSL connected in series with an alarm circuit, since it may happen that the called subscriber may leave the telephone until the toll operator has established the connection at the other end.

If, on the other hand at the end of the conversation, the toll operator withdraws her plug before the subscriber releases, relay Tr releases, opening at its front contact the circuit for relay Ar , and closing at its back contacts circuits for relay Br and Er . Relay Ar releases slowly and will allow relay Er to come up via its front to back of Tr , and Or , being slow releasing, will allow Br to energize and be saturated to the back of Tr . The circuit for Er , after having been opened at the front of Ar , will be

kept closed at the front of B_r , and thus a long alternating current will be sent out to the toll line.

With this long impulse relay P_{rr} releases 5 and to its back contact B_{rr1} operates and locks. By the right inner front contact the sequence switch is driven out of 13, through 15 to position 17, where the brush carriage is restored. The sequence switch then advances 10 to position 18, where G_{lr} checks, via cam K, to the back of R_{br} , whether the impulse is already over, and if so, G_{lr} operates and at its front contact drives the sequence switch to its normal position. The 15 trip spindle P_2 restores in position $13\frac{3}{4}/15\frac{1}{4}$ and $17\frac{3}{4}/5$ to its off home contact, in the usual way.

At the toll exchange the locking circuit for relays J_r , H_r , and K_r also being opened 20 at the front of T_r , all these relays will release.

Release from busy position 12

If the toll operator releases due to the 25 fact that the called subscriber has been found busy, relay G_{lr} operates via cam D, back of P_{gr} to the front of R_{br} , and immediately opens the ground for the armature of B_{fr} , which was supplied via the back contact of 30 G_{lr} from cam G. A while later, when P_{rr} releases, B_{rr1} also operates and locks and drives the sequence switch through positions 12/15. At the left hand back contact of B_{rr1} , the ground for the armature of B_{fr} 35 is definitely opened, to prevent a false impulse from being sent out to the line. On the other hand relays B_{cr} and R_{rr} , which are energized in position $11\frac{1}{4}/12\frac{1}{2}$ to ground on cam Q, will keep energized, beginning in $12\frac{3}{4}/13\frac{1}{2}$, via cam L to the 40 left middle front of B_{rr} ; this in order to prevent R_{sr} from operating and sending out ringing current.

Premature release

45 Any kind of premature release is characterized by the release of P_{rr} and by the operation of B_{rr1} in the regular way. In all cases, by the right inner front of B_{rr1} , the sequence switch is advanced, or in positions $7/9\frac{1}{2}$ the sequence switch is advanced 50 at the back of G_{lr} , on account of the circuit for the latter relay being opened at the back of B_{rr1} . To the left inner front 55 of B_{rr} , between positions $4/10\frac{1}{2}$, relay I_{rr} operates and at its back contact the loop towards the instepping circuit of the register is opened, and thus the register will be caused to release. This is necessary on account 60 of the fact that from the selection beyond position the cord may release only from the register. Whenever B_{rr1} is energized, at its right outer front contact battery is connected to the inner winding of 65 P_{gr} , and as soon as the releasing impulse

is over, P_{gr} will also energize to the back of R_{br} , and it also locks to cam F. At the right change-over combination of P_{gr} , I_{rr} is disconnected from the front of R_{br} and N_{cr} is connected to this front instead. The 70 function of relay N_{cr} is to register a new call, if such is originated during the release. In fact, in case of a new call, relay N_{cr} will energize via front of P_{gr} to front of R_{br} , and will lock until position 1. At 75 the front of N_{cr} , the sequence switch is moved through position 1 to 2, and the call then progresses in the regular way.

If a premature release occurs during the hunting for a register, test potential is 80 placed from the right outer contact of B_{rr1} , via cam X, to the home terminal "g" of the register chosen in order that the cord should stop on this terminal in case no free register has been found. 85

Permanent glow

If, due to discharges on neighbouring lines, relay R_{ar} and R_{br} in the trunk circuit operate, and thus a call is originated, 90 when the cord circuit becomes connected to the register and no dialling follows, relay P_{gr} will operate from the register and lock. The sequence switch will then be driven out by the left front contact of P_{gr} , through 95 all positions except the "return on premature release" position, and relay N_{cr} is again connected towards the front of R_{br} , via the front of P_{gr} . Thus, also if a call is originated in such a case, it will be taken 100 by relay N_{cr} , and the sequence switch will be driven beyond position 1.

It will be remarked that in any case, when B_{rr1} or P_{gr} operates, the ground from the armature of B_{fr} being removed, no impulse 105 will be sent out to the toll operator, and thus no false signal will be given.

Back release

If back release is wanted, connections 110 called for under note 1 are to be provided, and in such a case, when the called subscriber releases, the selector may move out of position 13 by the front of G_{lr} , which is energized to the back of G_{sr} . An impulse will 115 be given towards the toll operator in the regular way, due to the opening of the front of C_{sr} . In this case, the sequence switch will stop in position 15, awaiting the release from the toll operator, which feature is necessary in order not to create a new call by the release impulse. Due to the energization of G_{lr} in 13, to the back 120 of C_{sr} , it will lock by its left hand front contact to cam G, and in this way lamp 125 GSL will light in position 15.

B. Automatic toll recording

The local recording trunk circuit is, during 130 the day, connected to the local toll office,

and if, during the night, it is required to transfer the calls to the distant toll exchange, the night key NK must be thrown. By the top change-over contacts of the night key, relay Rhr is connected towards the front of Tar and Tqr , and the busy lamp is disconnected therefrom. At the bottom change-over spring combination of the night key, the ordinary ringing relay Srr is disconnected and the 50 cycle relay Rcr is connected towards the front of Tar . Furthermore, at the bottom make contact of NK, relay Rdr is connected to the group selector; this in order to make the trunk busy for outgoing calls (automatic to toll) in case the toll operator has originated a call towards the automatic exchange.

When the trunk circuit is picked up by a 2nd group selector, relay Tar operates and to its right front contact the switching relay Rhr also operates; this in order to transfer the front of Rbr towards the relay combination Rgr , Rfr and Rlr . To the left front of Tar , relay Rcr operates and sends out a short alternating current impulse towards the distant toll office. Relays Rr and Dr operate, and relay Fr operates in turn to the front of Dr and locks to the back of Gr . Lamp GL will light to the front of Fr and an operator will answer the call by plugging into the jack LJ . Relay Tr will operate, and to its front, via front of Fr , relay Gr operates, disconnecting the lamp and opening the locking circuit for Fr , which releases: Relay Gr will lock via its front contact to the front of Tr , and will remain energized during the whole connection.

When the plug is inserted, relay Er is caused to operate for a short time, in just the same way as on an outgoing call, and thus a short alternating current impulse is given to the line. By this impulse, from the front of Rbr , via front of Phr , relay Rlr is caused to energize and will lock via its make before break combination and back of Rgr to the front of Tqr . At the right front contact of Rlr , a circuit is prepared for Rfr , and when the impulse is over, the latter relay will also operate to the back of Rbr and lock to its own front contact. At the change-over contacts of Rfr , the local recording trunk is switched over to the toll line, and the bridge relay Brr will operate via the repeating coil. At the left outer front contact of Rfr , a circuit is prepared for relay Pgr , towards the front of Rbr .

Due to the operation of Brr , the local recording trunk is kept busy until the toll operator releases the connection. In fact, when this happens, an impulse is again given to the line, in the known manner, which will cause the operation of Rgr , which relay will lock by its outer winding, via its right hand make before break combination, to the front

of Tqr . At the right change-over combination of Rgr , the circuit of R/r is opened, which relay releases and in turn Rfr will also release. Thus the toll line will be disconnected from the local recording trunk. Relay Rhr will remain energized via the front of Rgr to the front of Rbr , as long as the impulse lasts. When the impulse is over, relay Rhr will also release. When Rfr releases, relay Brr also releases and thus the local recording trunk is under the control of the automatic subscriber only. When the automatic subscriber releases, relay Tqr will release and Rgr also releases in turn, and everything will be in the normal condition.

If the automatic subscriber releases first, relay Rgr will keep energized only as long as the releasing impulse lasts, since, after the release of Rfr and Brr , relay Tqr will also release. It can be seen from the above that the local recording trunk is kept busy until the toll operator releases, even if the automatic subscriber should release first.

It may be seen that when the night key NK is not thrown, the two circuits, i. e., the long distance dialling toll trunk and the local recording trunk, are independent of one another, and either of them can be used without interfering with the other.

Although this invention has been shown and described as applied to a particular system, namely a machine driven telephone system it is not limited but only in accordance with scope of the invention as defined by the appended claims.

What is claimed is:

1. A telephone system comprising a toll exchange, an automatic exchange, a two wire trunk extending between said exchanges, means at said toll exchange for transmitting alternating current impulses over said trunk to said automatic exchange to position automatic switches therein and means whereby said trunk is adapted to be employed as a recording trunk for calls from said automatic exchange to said toll exchange.

2. A telephone system in accordance with claim 1 wherein a relay device is located in said automatic exchange and wherein upon the extension of a call originating in the automatic exchange to a local recording trunk, said relay device is adapted to be operated to effect the connection of the local recording trunk to said two-wire trunk and the transmission of an alternating current impulse to said toll exchange to indicate the presence of the call.

3. A system in accordance with claim 2 having a second relay device associated with said local recording trunk and wherein said second relay device is adapted to be operated upon the connection of the local recording trunk to the two-wire trunk to busy the

two-wire trunk and to place the local recording trunk under the control of the toll exchange independently of the calling subscriber's line.

5 4. A system in accordance with claim 2 having a switching device associated with the local recording trunk and wherein said switching device is adapted to disconnect the normal connection of said local recording trunk and connect the latter to alternating current receiving and transmitting means.

10 5. A telephone system comprising an automatic exchange, a distant exchange, a trunk line extending between said exchanges, means adapted to transmit alternating current impulses from said distant exchange to said automatic exchange over said trunk, and means located at said automatic exchange adapted to transmit to said distant exchange over the said trunk alternating current impulses to give a progress indication and supervision of the connection.

15 6. A system in accordance with claim 5 wherein said means located at the automatic exchange comprises a group of relays adapted to be controlled to effect the transmission of said alternating current impulses.

20 7. A system in accordance with claim 1 wherein a group of relays is provided at the toll exchange and is associated therewith said two-wire trunk, and wherein the relays of the group are so related to one another that different signals are adapted to be given by subsequent alternating current impulses received from the automatic exchange.

25 8. A telephone system comprising a first exchange having a toll position, a second exchange having automatic switches, a trunk extending between said exchanges, means for transmitting alternating current impulse over said trunk, a relay device at said second exchange adapted to enable the handling of a new call while the normal circuits are being restored as a result of a premature release of a previous call.

30 9. A system in accordance with claim 8 having an alternating current impulse receiving relay at said second exchange wherein said relay device, at the second exchange, upon a premature release is adapted to be placed under the control of said impulse receiving relay and to be operated upon the initiation of said new call and to lock up to restore the circuits and then effect their re-operation for said new call.

35 10. A system in accordance with claim 8 wherein said relay device is adapted to restore the circuits to normal in the event of a faulty call (i. e. calls due to changes on neighboring lines).

40 11. A telephone system comprising a toll exchange, an automatic exchange, a two-

wire trunk extending therebetween, means for transmitting alternating current impulses over said trunk, a connecting circuit at said automatic exchange, and means in said connecting circuit adapted to be operated to ringer the called subscriber by transmitting alternating current impulses over said trunk in the event such subscriber should leave his telephone when the connecting circuit is in the talking position.

45 12. A system in accordance with claim 11 wherein a ringing relay is provided in the connecting circuit and the said means in the connecting circuit comprises two relay devices adapted to be placed under the control of the alternating current impulse receiving relay at the incoming end of the trunk line when said connecting circuit is in the talking position whereby said ringing relay is adapted to be controlled by the alternating current impulses transmitted from said toll exchange.

50 In witness whereof, we hereunto subscribe our names this 5th day of April, 1930.

CHARLES EDWARD STEVENS. 90
ARMAND MAMOR.
